APPARATUS FOR LAUNDERING CLOTHES

James N. White, Denver, Colo.

Application December 26, 1930, Serial No. 504,840

2 Claims. (Cl. 68—18)

This invention relates to a method and apparatus for laundering clothes and more particularly to an improved method and apparatus for continuously carrying out the several operations 5 to which the clothes must be subjected.

A number of different kinds of machines are necessary to carry out the process of laundering clothes and the present day method of transferring the clothes from one machine to another 10 by manual labor requires considerable time, and, when the clothes are wet, involves laborious, disagreeable, and unhealthful work. This, together with the idleness of the machine during these manual operations, renders the present day process of laundering very inefficient and costly.

It is one object of this invention to provide a method and apparatus that will overcome the above difficulties.

Another object is to provide a method and apparatus that shall be continuous in operation and automatically transfer the clothes from one machine to another without the necessity of manual handling of the clothes.

Another object is to provide a method and apparatus for laundering clothes that will permit the clothes to fall by gravity from one machine to a conveyer, the latter operating to transfer and deposit by gravity the clothes into the next machine.

Another object is to provide a method and apparatus for laundering clothes that will permit the clothes in one machine to drop by gravity to another machine, for providing continuous operation.

Another object is to provide a method and apparatus for laundering clothes, comprising a plurality of machines having means intermediate thereof for automatically transferring the clothes from one machine to another, as well as means for keeping the several batches of clothes separate, and depositing them in individual bins in the next machine.

A further object is to provide, in a method and apparatus for laundering clothes having the above characteristics, novel means for retaining, with the batches of clothes in the several bins in the initial machine, the means of identifying the several batches, the said means being adapted to transfer each marking tag with its respective batch of clothes to the next machine.

A further object is to provide a method and apparatus for laundering clothes that will greatly reduce the time for carrying out the several laundering operations, thereby greatly decreasing 55 the cost of such operations, as well as reducing

the number of machines required to carry out a given volume of work.

A still further object is to provide a method and apparatus for laundering clothes which will eliminate the laborious and unhealthful work of 5 handling wet clothes.

The above and other objects, such as the arrangement, location of parts and machines and many other desirable features, will be apparent throughout the further description of the invention, considered with the accompanying illustrative drawings, wherein like reference characters refer to like parts throughout the several views.

It is to be understood that many changes may be suggested to those skilled in the art, without departing from the spirit and scope of the invention and the appended claims, and it is to be further understood that the drawings are not designed as a definition of the invention, the latter 15 being defined in the appended claims.

In the drawings—

Fig. I is a view in elevation, partly in section, of an apparatus embodying the invention.

Fig. II is a plan view of a detail of the conveyer 25 mechanism embodying the invention.

Fig. III is a section along the line 3—3 of Fig. I showing the tub and associated parts in normal position for washing operation.

Fig. IV is a section similar to Fig. III but showing the tub and associated parts in position at 30 the extreme of the fluid dumping movement.

Fig. V is a view similar to Figs. III and IV but showing the tub and associated parts and the cage at the end of their respective movements in 35 the operation of dumping the clothes.

Fig. VI is a partial view similar to Fig. I illustrating another embodiment of the invention.

Fig. VII is a view in elevation of still another embodiment of the invention, and

Fig. VIII is an enlarged detail view of Fig. VII.

The invention consists of a plurality of machines for handling clothes (here illustrated and described as a washing machine and an extractor), and means intermediate thereof for transferring the clothes from one machine to another without assistance of manual handling of the clothes.

In the form shown, Figs. I, II, III, IV and V comprise a washing machine, 10, supported a distance 50 from the floor 12, or other suitable supporting surface, provided with driving mechanisms 13 and 14. For the purpose of this disclosure the washing machine 10 is identical with that illustrated and described in my application, Serial No. 462,655, 55

dated June 20, 1930; however, for the sake of simplicity the following description is given:

The washing machine 10 is rotatably supported in supporting members 15, and comprises an inner 5 perforated clothes container 16, having a sliding door 17, an outer tub 18, the latter being substantially semi-circular in shape. The cover 19 is fixed to and supported by the tub 18 but at a distance from one of the upper edges of the tub, as shown 10 at 21. This provides a longitudinal opening along one side of the tub so that when the tub 18 is rotated in a counter-clockwise direction, the fluid within the tub will pour out through the longitudinal opening 21 and be directed to a drain or 15 gutter, 22, by means of aprons, 23 and 24.

The apron 23 may be fixed to the supporting members 15 in any suitable manner and the apron 24 is also supported by the members 15, but is pivoted thereon by a plurality of mechanisms spaced 20 apart throughout the longitudinal length of the tub, each of which mechanisms comprises a support 25, having a pin 26, extending outwardly therefrom for engaging a slot or groove 27 provided in the lower end of the apron 24. The normal position of the apron 24 is shown by Figs. III and V and it may be biased to this position by yielding means 28 or by weighting its lower end as shown at 29. The upper end of the apron 24 terminates in a curved portion 31 for engaging spaced 25 lugs 32 provided along one edge of the cover member 19. It will be noted that this edge is provided with an outwardly supported flange 33 which serves to assist in the directing of any fluid that may splash out of the opening 21 during operation 30 of the machine.

Fig. IV illustrates the machine in its extreme fluid-dumping position. This position is obtained by rotating the tub and cover member 19 counter-clockwise by the driving mechanism 14, and it 40 can be readily seen from the drawings that the lugs 32 will engage the curved portion 31 on the upper end of the apron 24, carrying the apron to the position shown in Fig. IV, whereby the fluid will be directed to the drain 22. This prevents 45 fluid from falling on the floor directly under the machine, the purpose of which will hereinafter be made plain. It will also readily appear from the drawings that upon rotating the tub 18 clockwise and returning the same to its normal position, the apron 24 will readily be brought back to its normal 50 position by the yielding means 28.

The cover 19 of the tub 18 is also provided with a sliding door 34, adapted to open by means of the groove 35, disposed between band 36 and cover 19, all of which structure is fully disclosed 55 in the above mentioned application. As stated above, the tub 18 and top 19 are rotated by means of the mechanism 14 while the cage 16 is rotated independently of the tub 18 by means of the driving mechanism 13. Likewise the details of the driving mechanism 13 and 14 are fully set forth in the above mentioned application.

Arranged between the bottom of the tub and the floor 12 is a conveyer 37, of any endless type, 60 carrying receptacles or containers 38, adapted to register with the several bins forming the inner structure of the cage 16. These bins are indicated at 39 in Fig. I as separated by means of the dotted lines. In the form shown, an extractor 41 65 is disposed at one end of the conveyer, and on a floor or supporting surface, not shown, below the floor 12 and so positioned that, as the conveyer 37, which is of the continuous type, and supported by suitable means as shown at 40, carries the 70 buckets or containers 38 around the end of the 75

conveyer through one of the openings 42 in the floor 12, the clothes are dropped into the several sections of the extractor. In order to keep the several batches of clothes separate it is necessary that the speed of the containers 38 be synchronized with the speed of the bins or compartments in the extractor. Means 43 is provided for this purpose and comprises a shaft 44, adapted to rotate the extractor at the proper speed, carrying, rigidly fixed to the shaft, a gear 45, adapted to 10 mesh with gear 46, carried by shaft 47, the latter being provided at its lower end with a beveled gear 48, meshing with a gear 49, carried on one end of a shaft 51, the latter also being provided at its other end with a gear 52 meshing with 15 a gear 53 fixed to shaft 59. The shaft 59 also carries a sprocket wheel 61 adapted to mesh with a sprocket chain 62, fixed to the edge of the conveyer and extending throughout a portion of its length to correspond with the amount of rotation required of the extractor. It can be seen, therefore, that so long as the sprocket chain 62 is not in engagement with the sprocket wheel 61, the extractor may rotate independent of the conveyer. Any approved means, not shown, may be 20 provided for breaking the connection between the extractor 41 and the chain 62 and likewise for rotating the extractor during the extracting process. It should here be noted that while only one conveyer and one washing machine is shown 25 associated with the extractor, it is to be understood that any number of conveyers and washing machines may be arranged, or one conveyer may be extended under a number of machines, so that one extractor may be employed to take care 30 of a number of machines. In this connection it might be well to say that the extracting process requires considerably less time than the washing process and the advantages of arranging a number of machines to utilize a single extractor will be 35 obvious to those skilled in the art, and such an arrangement is within the scope of this invention.

In order that the several batches of clothes may be identified, a novel means, comprising cups 64 45 positioned adjacent the upper edge of the tub and on the opposite side from the groove 21 at substantially the center of each of the bins 39, these cups having their upper ends open so that when the washing machine is rotated in a clockwise direction for dumping the clothes into the containers 38 (see Fig. V), the marking tags will fall simultaneously with their respective batches 50 of clothes and will continue on through the several operations.

The operation of the embodiment of this invention above described is as follows:

The clothes are put into the several bins 39 of the washing machine by way of the doors 34 and 17, placing the respective marking tags in the cups 64, after which the doors are closed and the driving mechanism 13 is operated for rotating the cage 16 a predetermined number of revolutions in one direction and then the same number in the opposite direction, for a predetermined length of time, after which the means 14 is operated to rotate the tub 18 in a counter-clockwise direction, emptying the fluid within the tub by way of the opening 21, aprons 23, 24, and drain 22. The means 14 is of the reversible type and with the present structure the fluid is exhausted from the tub by the time the slot or opening 21 has reached its lowermost position; since the means 14 is so designed as to reverse 70 the direction of the tub, upon completing its 75

previous direction the clean or new fluid is immediately admitted to the inner part of the tub and a sufficient quantity of fluid is quickly supplied within the tub.

5 The mechanism for supplying fluid such as wash water, soap and bluing, is also fully disclosed in the above mentioned application and does not form any part of this invention.

Upon completion of the several successive washing operations and fluid dumpings the tub and the cage 16 are rotated simultaneously in a clockwise direction by means 14 and 13 respectively, at which time both the doors 34 and 17 are open and the clothes and the tags are dropped by gravity 10 into the containers 38, after which time the conveyer is operated by any suitable driving mechanism to convey the clothes and rotate the extractor, during which time the means 43 comprising gears, shafts, sprockets, chain and associated 15 parts 44 to 62 operate to cause the clothes contained in the several containers 38, with their respective tags, to be deposited by gravity into respective individual compartments of the extractor. Immediately upon completing the 20 dumping operation of the clothes from the washing machine into the containers 38, the washing machine may be immediately refilled with clothes for a repetition of the same operation.

Fig. VI illustrates a slightly different embodiment of the structure disclosed by Fig. I in that openings 50 are provided in the floor 12 for dropping the clothes from the washing machine through the said openings into a conveyer supported beneath the floor 12, the remaining portion of the apparatus together with the operation, being identical.

Fig. VII illustrates another embodiment of the invention, wherein a plurality of machines, 10, are disposed on a floor or supporting surface 12, the latter having chutes 71 extending downwardly therethrough and connecting with a main chute 73, the latter adapted to convey the clothes to an extractor 41, positioned on a lower floor or supporting surface, not shown. Each of the 15 chutes 71 is provided at its bottom end with doors 74, for selectively connecting them with the main chute 73. The extractor may be rotated by any suitable automatic means or manually, for receiving the several batches of clothes in separate 20 bins. The doors 74 may be manually or automatically operated, as desired. The latter embodiment provides a convenient arrangement for employing a single extractor with a plurality of washing machines, and in some instances may be 25 more cheaply constructed. The washing machines employed by the various embodiments are of the gravity dumping type such as that described above, or those disclosed in other patents and applications of the same inventor.

60 It will be obvious that the belt conveyor may extend under a plurality of washing machines positioned in series, preferably end to end, and receive clothes from any or all of such machines and convey the clothes to the extractor.

65 There is thus provided a method and apparatus for laundering clothes that will transfer clothes from one machine to another without the manual handling of the clothes. The present method and apparatus greatly reduces time heretofore required to carry out the laundering operations and in so doing there is provided a method and apparatus which will decrease the number of machines heretofore required for completing a given volume of work. It has been found in practice 70 that one machine of the present apparatus will

turn out substantially the same amount as two machines of the same size heretofore provided. The manual labor heretofore required is substantially reduced and the machine can be provided at a reasonable cost in comparison with the cost 5 of machines now in use. Further, it has been found that the work accomplished by the present method and apparatus is superior in every respect to that accomplished by the machines where it is necessary that the clothes be manually 10 handled several times during the laundering operations. Any possible chance of the clothes becoming snagged or otherwise torn is obviated. The disagreeable, laborious and unhealthful work of transferring wet clothes by hand is entirely 15 eliminated, as is the flooding of the laundry floor which results therefrom. Also much floor space is saved by positioning the conveying means under the washing machines instead of in the usual aisles between the washing machines which are 20 ordinarily positioned in lines end to end with aisles between.

Other advantages such as the quick disposition of the soiled fluid from the washing machine, whereby the sediment and dirt within the machine is positively disposed of, the quick manner in which the machine may be refilled with fluid for a second operation, the transferring of the clothes by gravity from one machine to another or by one machine to a conveyer, the latter transferring the same to the next machine, by gravity, the synchronism between the operation of the several mechanisms and other advantages, will appear to those skilled in the art, all of which fall within the spirit and scope of the specifica- 35 tion and claims.

While the invention has been described as a method and apparatus for laundering clothes, it is to be understood that the same apparatus may be employed for bluing, dyeing, drying, etc., of 40 clothes, and generally for the handling of fabrics and textiles wherever the same are subjected to fluid within a machine, and while only a certain number of washing machines have been shown, in combination with an extractor, it is to be expressly understood that any number of different kinds of machines may be employed and still remain within the scope of the invention. Other changes, modifications, substitutions, additions 45 and omissions may be made in any part or parts of the method and apparatus without departing from the spirit and scope of the invention as defined by the appended claims.

What I claim is:

1. In apparatus for treating fabrics, a rotatable tub having a cover spaced therefrom to provide a longitudinally extending opening along the back upper edge of the tub, means for rotating said tub to bring said opening to the under side of 60 said tub whereby to dump fluid from the tub through the opening, a fluid diverter swingingly mounted at the rear of the tub and normally upright, means operable by the tub during such rotation adapted to swing the diverter to inclined 65 position with its upper edge beneath said opening as such rotation brings the opening toward the bottom of the tub, whereby to divert fluid, dumped through said opening, to the rear of the tub, and means for returning said diverter to 70 normal position.

2. Apparatus for laundering clothes comprising, in combination, a semi-cylindrical tub having a cover, openings for receiving clothes into the tub, a longitudinal opening along the rear 75

upper edge of said tub, a conveyer beneath said tub and adapted to move longitudinally thereof, means to rotate said tub in one direction to bring said clothes-receiving opening to the bottom of said tub whereby to dump clothes from the tub by gravity into said conveyer, means to rotate said tub in the opposite direction to bring said longitudinal opening to the bottom of said tub whereby to dump fluid from said tub through said opening, a swingingly mounted fluid diverter

normally back of said conveyer, means, operable coincidently with the rotation of the tub in dumping fluid, to swing said diverter into inclined position with its top over said conveyer and beneath said longitudinal opening, whereby to divert the dumped fluid away from said conveyer, and means to return the diverter to normal position back of said conveyor. 5

JAMES N. WHITE. 10
